UNITED STATES PATENT OFFICE

JOSEPH DE FRANCISCI, OF BROOKLYN, NEW YORK

HYDRAULIC PRESS

Application filed July 9, 1926. Serial No. 121,290.

My invention is a hydraulic press, the same being an improvement on, or for use in connection with, presses of the character disclosed in my prior Patent No. 1,502,021, patented July 22, 1924, although it is to be understood that my present invention is useful in conjunction with other kinds of presses wherein a motive fluid is utilized for the operation of the motor, the latter being associated usually with a material cylinder and an extruding die.

The invention pertains more especially to a material compacting mechanism co-operable with the material cylinder of the press for the purpose of applying pressure to the material contained within said cylinder, whereby such material is forcibly compressed with a view to increasing the density of the mass.

One object of the invention is to apply pressure to the mass of material, and to continue the application of such pressure for a determined period, with a view to precluding expansion of the mass of material in the period which elapses between the initial condensation of the mass and the application of pressure to such mass by the operation of the extruding plunger or ram constituting an element of the hydraulic motor, the latter being an element of the press.

A further object is the control of the packing mechanism, the same being dependent in a measure upon the movement of the extruding plunger or ram, which packing mechanism is initially started into operation by the movement of a manually actuated member with a view to effecting the power stroke of the packing plunger. Thereafter, the packing mechanism is set into action on the upward travel of the extruding plunger or ram to the end that the packing plunger is withdrawn by fluid pressure from the material cylinder, whereby the packing mechanism is restored to normal position prior to reversing the material cylinder from a charging position to a service position.

Broadly stated, my invention is a hydraulic packing mechanism associated with a press and with reversible material-carrying cylinders, whereby on the upstroke of the ex-

truding plunger or ram the packing mechanism is set into action for effecting the withdrawal from the material cylinder of the packing plunger.

Other functions and advantages of the invention will appear from the following description taken in connection with the drawings, wherein—

Figure 1 is a side elevation of my packing mechanism associated with a hydraulic press, the extruding plunger and the packing plunger being shown in their normal raised positions.

Figure 2 is a longitudinal sectional view through the control valve for said packing mechanism.

Figures 3, 4 and 5 are views partly in section and partly in elevation of the control valve and a valved by-pass in the different positions which said valve and the by-pass assume on the up and down travel of the extruding plunger or ram.

Figure 6 illustrates views in side and end elevation respectively of the rotary member of said control valve of the packing mechanism.

In Figure 1 there is shown generally a hydraulic press adapted for the manufacture of macaroni, said press being of the type disclosed in my Patent No. 1,502,021. In said Figure 1 there is shown a hydraulic motor including a power cylinder, A, and an extruding ram or plunger, B, a plurality of connected material cylinders, C, C', in reversible relation to the plunger or ram, B, an extruding die, D, supported by a carrier, D', and a master valve, E, operated by a hand lever, such as e, and associated with a feed pipe, f, and a return pipe, f', together with other pipes, g, g', leading from the master valve, E, to the power cylinder A, said pipes g, g', leading a motive fluid between the valve and the top and bottom parts of said power cylinder. The several mechanisms are constructed and operated as disclosed by my aforesaid patent, and do not require further illustration and description here.

The material compacting mechanism of the present invention is shown in Figure 1 as operatively mounted on the frame of the

power press, and as there shown, a bracket F is solidly attached to the cylinder A, or to one of the press columns, although the means for mounting the packing mechanism may be changed by a skilled constructor. Said bracket carries a hydraulic cylinder, G, of said packing mechanism, and within said cylinder operates a packing plunger, G', the lower part of which is provided with a head G², the diameter of which corresponds to the internal diameter of either material cylinder, C, C'.

To the packing cylinder G are connected pipes h, h', leading from a control valve I forming an element of the packing mechanism, one of said pipes as h being attached to the upper head of the packing cylinder G, whereas the other pipe h' is attached to the lower part of said packing cylinder.

The control valve I of the packing mechanism is shown more particularly in Figures 2 and 6, whereas the relation of said control valve to the by-pass is illustrated in Figures 3 and 5, inclusive. As shown, the valve I comprises a shell, i, and a plug rotatably seated within the shell, said plug embodying a frusto-conical body portion, j, and a cylindrical stem, j'. The valve shell i is provided interiorly thereof with a chamber n forming conical seat, and with a longitudinal axial bore for the reception, respectively, of the conical body j and the stem j', whereby the valve plug is seated for rotative movement within the shell i. The stem j' of the valve extends through one end of the shell, said protruding end of the stem having a squared portion j² and a threaded portion, j³, see Figures 2 and 6, and on the threaded portion is screwed a nut k operating to compress a spring k' for the purpose of exerting pressure on the valve plug for drawing the conical body portion j snugly to its seat provided by the conical part of chamber n within the valve shell, see Figure 2. The valve shell is provided with suitable means for the attachment of the pipes required for the flow of the motive fluid, and in addition thereto the valve shell is provided with a return chamber m for the motive fluid, which chamber m surrounds the valve stem j', see Figure 2. The conical part of the rotary valve occupies a part only of the chamber n, one part of which chamber is taken up by the conical valve seat, but toward the end of the valve shell, this chamber n is interiorly threaded. Into this threaded part of chamber n is screwed a plug or closure o, made to fit tightly by a packing o' to preclude leakage of the motive fluid; said plug o being in facing relation to the end face of the valve plug j, and being spaced with respect thereto so as to leave a space or subchamber indicated at n', through which is adapted to flow the motive fluid from the source of supply.

The rotary valve plug is provided in its

conical portion with a series of feed channels or grooves p, q, r, which extend to, and open through, the end face of the conical body j, see Figure 6. In addition to these feed channels, the conical part of the valve is provided with a plurality of return passages s, t, u, the latter opening through the conical face of the valve body and in the required relation to the feed channels. These return passages s, t, u, extend radially with respect to the valve body, and they open into a common return passage v provided axially within the valve body and the stem j thereof, said common return passage having a port v' which opens into and communicates with the return chamber m provided within the valve shell, see Figure 2.

Motive fluid from a source of supply, such as a pump or accumulator, is conveyed to the control valve by a pipe H, one end of which is attached to the valve shell to feed the fluid through a port h⁴, with which is adapted to register one of the feed channels p or q, according to the position occupied by the valve plug within the valve shell, whereby the fluid under pressure flows from pipe H, through port h⁴, one of the channels p or q, to the subchamber n', and through this chamber n' to one or the other of the pipes h or h', whereby fluid under pressure may flow to the upper part or the lower part of the packing cylinder G for the actuation of the packing plunger by the energy of said motive fluid.

A return pipe H' for directing the flow of motive fluid from the valve back to the pump or accumulator is connected to the shell i for communication with return chamber m, and to this chamber m and pipe H' flows the motive fluid from one end to the other of the packing cylinder, such return of the motive fluid taking place through the control valve concurrently with the flow of motive fluid under pressure and through said valve from the other end of said packing cylinder, whereby fluid under pressure is admitted to one cylinder end, whereas fluid from the other end of the cylinder flows out of the same under the travel of the packing plunger.

The return passages, s, t, u, are formed in the valve body in the same plane, see Figure 6, and the feed pipe H and flow pipe h, h', are attached to the valve casing in the same plane, in which are positioned the return passages aforesaid. The longitudinal return passage v within the valve extends from ports which open into the chamber m to the return passages s, t, u, so as to serve as a common return from either end of the packing cylinder, to the chamber m and thence to the single return pipe H'. This longitudinal return passage v does not open through the face at either end of the valve, but for manufacturing purposes in boring the return passage v it is bored through the end face at the enlarged conical part j of the valve, and there-

after the end is plugged or suitably closed.

Means are provided for rocking the valve, i. e. for axially turning the member comprising the parts j , j' , and to this end a lever arm J is fitted on the angular part j^2 near one end of the valve stem j' . To the outer end of this lever arm is pivoted a vertical stem J' , extending downwardly for attachment to a manually operated lever K which is provided for turning the valve member j , j' , said lever being fulcrumed at k^2 on the packing cylinder and pivoted at k^3 to the stem J' , said lever being provided with a weight K' to depress the valve arm J and 15 tend to turn the valve I to a position which establishes a flow of the motive fluid through pipe h' into the lower part of the packing cylinder whereby the packing plunger is impelled to move upwardly.

In the service of the press, the material is charged in one cylinder as C' , and compacted therein by the downtravel of plunger G' , G^2 , as presently described, whereupon the connected cylinders C , C' , are reversed in position by swinging the same around a press column and to thereby bring the charged cylinder into alignment with the power plunger or ram B and the extruding die D .

The master valve E is now operated to 20 direct the flow of motive fluid into the upper part of the power cylinder for applying pressure to the ram B and forcing it downwardly within the charged cylinder for extruding the material through die D , as set forth in my aforesaid patent. At this time, the operator proceeds to charge another batch of material into the empty cylinder which is now in alignment with the packing plunger, and when the batch is deposited therein the packing mechanism is in readiness for operation. At this period, power plunger or ram B is descending, and the control valve I is in a neutral position, as indicated in Figure 3, by which is meant that the valve is so adjusted 25 that no fluid passes into either pipe h or h' into the packing cylinder G , although the motive fluid continues to flow from pipe H through the valve I by reason of the registration of return port s with the port h^4 of pipe H (Figure 3) so that the inflowing fluid admitted by pipe H flows through port h^4 , port s , longitudinal port v , chamber m , and through pipe H' back to the pump.

One material cylinder having been 30 charged, and with the ram or plunger B operating in the other material cylinder, the operator now operates the valve lever K by pressing upwardly on the lever K to shift the stem J' and the valve arm J upwardly to 35 the position of Figure 5, thereby turning the valve plug within the valve shell and moving port s out of register with pipe H , and at the same time bringing the feed channel q into register with port h^4 of pipe H , feed channel r into register with the pipe h , and

return passage u into register with pipe h' (Figure 5), thus establishing the flow into the upper part of packing cylinder G of motive fluid under pressure, the inflowing fluid passing from pipe H , port h^4 , feed channel q , chamber n' , thence to feed channel r , and pipe h to the upper end of cylinder G , whereas the idle fluid within the cylinder G is displaced by the downtravel of plunger G' and flowing out of said lower cylinder end 40 through pipe h' , return port u , passage v , chamber m , and by way of pipe H' to the pump. Fluid under pressure is thus admitted to the upper part of packing cylinder G , and applies its energy to plunger G' , G^2 , for imparting the downtravel thereto, whereby plunger head G^2 acts upon the batch of material deposited in cylinder C for compacting the material therein.

In the use of the press for the manufacture of macaroni, the material is extruded slowly through die D by the downward movement of the plunger or ram B within one cylinder, as C , and this relatively slow extrusion action allows a period of time which is more than sufficient for charging the other material cylinder, as C' , with another batch of material and for compacting such batch within the material cylinder C' before the extruding operation is completed within first cylinder C . During such period required for the completion of the extruding operation, and for the ram to travel upward toward the normal position, the packing plunger G' , G^2 , remains under pressure of the motive fluid, and is in service within cylinder C' , and exerts pressure upon the batch of material in said cylinder as C' , whereby such batch in said cylinder C' is precluded from expanding within the cylinder for the remainder of the period required for the plunger or ram B to complete the extruding operation, and for said ram or plunger to travel upwardly toward its normal position.

As disclosed in the patent, the master valve E for the press is operated automatically to reverse the direction of travel of the ram or plunger B when such ram completes its downward travel, and to thus change the movement from a down movement into an up movement, during which upward movement of the ram back to normal position the pressure is maintained within the upper part of the packing cylinder G , so as to keep the packing plunger G' , G^2 in contact with the 115 batch of material within cylinder C' for precluding expansion of such batch at the specified period, and this is obtained by the flow of motive fluid from pipe H , through the valve in the position of Figure 5, pipe h from valve I to cylinder G . With the packing plunger G' , G^2 , thus retained in the lowered position within cylinder C' , the ram or plunger B moves upwardly within cylinder C 120 so as to be returned to a raised position, the 125

motive fluid from master valve E flowing by pipe g to the lower part of the power cylinder A in effecting the up movement of the plunger or ram B. At a desired period in the upward movement of ram B, the control valve I is reversed automatically as will hereafter appear, to depress the arm J to the downwardly inclined position of Figure 4, which reversal of the valve changes the plug from the position of Figure 5 to that of Figure 4, and which reversal shifts the passages g , r , out of register with pipes H, h , and return passage u out of register with pipe h' , whereby such reversal from Figure 5 to Figure 4 brings the passage p into register with feed pipe H, and the passage r into register with pipe h' , whereas return passage t registers with pipe h . As a result of such valve reversal, the motive fluid is supplied to the lower part of packing cylinder G, and the fluid present into the upper of said cylinder G is displaced by the upward travel of the packing plunger, the inflowing motive fluid passing through pipe H, port h^4 , thence by passage p to chamber n' , thence by passage r to pipe h' to the lower part of cylinder G for raising the plunger G' , G^2 , but the liquid displaced by such upward movement of plunger G' , G^2 , flows out of the upper part of the cylinder by way of pipe h , passage t , to longitudinal passage v , chamber m , and by pipe H' back to the pump.

The liquid from the pump to the control valve I flows substantially constantly through the valve I the enlarged conical body j of which valve is exposed to the pressure of the liquid flowing through chamber n' . The valve is thus held by liquid pressure to its seat, aided in a measure by the action of spring h' , and when the valve is rocked to the position of Figure 5 for feeding liquid to the upper part of packing cylinder G, and to effect the down travel of the plunger G' , G^2 , the pressure of such liquid in chamber n' against the end face of the conical valve part j acts to retain the valve in said position against the ponderosity of the weight K' acting on the valve arm J, to the end that said valve plug will remain in the position of Figure 5 during the downward movement of packing plunger G' , G^2 , and while such packing plunger in said lowered position within the material cylinder and during a part of the upward travel of the extruding plunger or ram B. There comes a time, however, in the upward travel of plunger B at which the pressure of the fluid in chamber n' and upon the end face of valve body j is relieved, for a brief period, whereby the valve plug is adapted to be turned automatically by the ponderosity of the weight K' acting on the arm J, so as to automatically reverse the valve I from the position of Figure 5, to the position of Figure 4.

65 This relief to the fluid pressure on the end

face of valve I is obtained by a by-pass, shown more particularly in Figures 3, 4 and 5, wherein L is a pipe coupled to the valve shell i for communication at all times with the valve chamber n' , see dotted lines in Figure 2, and indicated also in Figures 3 to 5. This pipe L is attached to the upper part of the casing or shell M of a relief valve, the lower part of said valve casing M being connected to a pipe L' , the other end of which pipe L' is attached to the power cylinder A at the lower part thereof, see Figure 1. The interior of the valve casing M is divided by a wall w to produce an upper valve chamber x and a lower piston chamber y , and in the wall itself is formed a longitudinal passage z and a transverse port z' . Within the valve casing M is a triple valve comprising a reciprocating member N having a reduced stem N' , a piston head O, and a ball valve P. The reciprocating valve member N fits slidably in the passage z provided in the division wall w , whereas the piston head O operates within the piston chamber y , and the ball valve P operates within the valve chamber x . It is to be noted that the cross sectional area of chamber y exceeds the similar area of valve chamber x , and thus the cross sectional area of piston valve O is in excess of the area of the ball valve P. Furthermore, the lower side of division wall w is shaped to constitute a seat w' , and the upper face of the piston head O is correspondingly shaped at o^2 and is adapted to be seated into liquid-tight contact with the seat w' on the elevation of the triple valve to the position of Figure 5. The diameter of the stem N' of the reciprocating valve is less than the diameter of the passage z in the division wall w , and in the lowered position of the triple valve, as in Figure 3, this reduced part N' of the valve member N is in the upper part of passage z , and for a part of its length is opposite to the transverse port z' . In said lowered position of the triple valve, Figure 3, the ball valve P rests on a seat provided by the upper face of the division wall w , and upon this ball valve acts an expansion spring P' occupying the valve chamber x and contacting at its opposite ends with the ball valve P and a part of the valve shell M. A relief pipe Q is coupled to the shell M for communication with the transverse port z' , and this relief pipe Q is attached to the return pipe H' , see Figure 1, thus affording a common return from the valve I to the pump.

The pipe L being connected with the chamber n' of the control valve I, fluid from said control valve is free to pass from said valve chamber n' to the valve chamber x of the relief valve, and thus the fluid acts on the valve P for depressing said valve to the seat within casing M to shut off the flow of any liquid through the relief valve to the pipe Q and pump return H' at a time when the

motive fluid is supplied through valve I to pipe h for effecting the downward movement of the packing plunger. With the packing plunger lowered upon the mass within one of the cylinders C or C', and with the power plunger or ram B moving upwardly, it is apparent that the motive fluid under pressure flows through pipe g into the lower part of the power cylinder, and such fluid under pressure flows also through pipe L' into the chamber γ at the lower part of valve shell M, the packing plunger G', G², being still lowered upon the charge within one of the cylinders C, C'. Owing to the difference in area of the piston head O to the valve P, and to the accumulation of pressure in chamber γ of the relief valve M, the motive fluid in the chamber γ operates to impart an upward movement to the piston O and valve member N, displacing the valve P upwardly, and moving the reduced stem N' of the valve member N relatively to the port z', such upward movement of the parts being arrested by the piston head O contacting with the seat w' on the under surface of the division wall. During the upward travel of the parts N, N', O, the stem N' opens the communication between chamber α and port z' for a brief period, so that the fluid present in the connection from chamber n' of valve I to the chamber α of the relief valve is free to pass out of chamber α through port z' to relieve the pressure on the end face of the control valve. Such opening of the by-pass is but momentary, however, because the pressure from cylinder A through pipe L' tends to move the piston valve O and valve member N upwardly in a continuous manner so that piston head O assumes a seated position and valve member N travels upward to close the port z', as in Figure 5, and on the continued upward movement of plunger or ram B, the triple valve is in the position of Figure 5 to shut off the continued outflow of fluid from chamber n' of valve I through the pipe L and the relief valve. On the cessation of flow of the motive fluid to the lower part of the cylinder A, as well as on the downstroke of the plunger or ram B, the pressure is reduced in chamber γ of the relief valve, whereupon the spring P' acts on the valve P to return it to the seat on the division wall, and to lower the parts N, N', O, to the position of Figure 3, the control valve I having been restored to a neutral position.

The operation is apparent from the foregoing description, but may be summarized as follows:

Material is charged in one of the two cylinders C, C', and the cylinders are reversed, so that for the purposes of this specification it is assumed a charged cylinder as C occupies a service position in register with die D, and power cylinder A, for ram or plunger B to extrude material from cylinder C

through the die, whereas an empty cylinder C' is below the packing plunger. The master valve E is operated by hand pressure on lever arm e, and ram or plunger B descends slowly within the cylinder C, but at this time the control valve I occupies a neutral position (Figure 3) and the packing plunger is elevated within the packing cylinder G. During the slow down movement of ram B, the operator has sufficient time within which to charge the empty cylinder C' with a batch of material, and thereupon the operator lifts the lever K from the position of Figure 1 to the upwardly inclined position of Figure 5, the effect of which is to raise the weight K' and the stem J', and also to turn the valve plug to the position of Figure 5, for establishing the flow of liquid from pipe H, through chamber n', pipe h, and to the upper part of cylinder G for effecting the down movement of plunger G', G², upon the batch of material in cylinder C' for compacting the same. At this time, the flow of fluid through valve chamber n' allows the fluid to act upon the enlarged end face of the conical part of the valve plug, whereby the pressure of the fluid against said end face retains the valve plug in the position of Figure 5, and overcomes the tendency of the weight K' to depress the lever K, so that the valve plug remains in said position of Figure 5 during the down travel of the packing plunger, and also for a period of time required for the ram B to complete its down travel and to start on its upstroke. Also, at this time, some of the fluid within chamber n' of valve I passes through pipe L to valve chamber α , and pressure is applied upon the valve P for holding said valve seated, Figure 3.

In the upward movement of ram B to withdraw said ram from cylinder C, the motive fluid supplied from master valve E by pipe g to the lower part of cylinder A, accumulates in pipe L', so as to establish a difference in pressure between that pressure applied to piston head O and that pressure applied to valve P, with the result that as the ram continues its up movement, the pressure in pipe L' exceeds the pressure in pipe L, and hence there is a reduction in pressure upon valve P, and such excess pressure through L' acts upon the piston head or valve member O to lift the parts N, N', O, P, for moving these parts first to the position of Figure 4, and then to the position of Figure 5. At such movement to Figure 4, the port z' is opened to return Q briefly as described, and the effect is to relieve the pressure through H and within chamber n', as a result of which the fluid pressure on the enlarged end face of the valve plug is reduced so that the pressure of weight K' turns the lever K and valve arm J from raised position (Figure 5) to lowered positions (Figure 4), and also to depress the rod or stem J' into a lowered

position relatively to the bottom part of the cylinder G. Such reversal of lever arms K, J, under the action of weight K' overcomes the frictional resistance to the rotative movement of the valve plug (the fluid pressure on which is momentarily relieved as stated), and the valve plug turns from the position of Figure 5 to the position of Figure 4, the flow of liquid being diverted so that the fluid under pressure flows into the lower end of cylinder G for raising the packing plunger, the return of liquid from the cylinder back to the pump due to the travel of the plunger in cylinder G and through the valve. The valve I having been reversed as described, it remains in such reversed position, with the levers K, J, inclined downwardly, during the upward travel of the packing plunger, but at a certain period in the service of the press, the ram B and the packing plunger both travel upward to withdraw said plungers from the respective cylinders C, C'. As the packing plunger nears the limit of its upward travel, the head G² strikes the lower end of the stem J', and as the packing plungers continues to rise, the stem J' is lifted mechanically by the packing plunger to turn the lever K and the arm J to horizontal positions, and thus restore the valve I automatically to a neutral position, at which time the flow of liquid is shut off to the lower part of the packing cylinder, to arrest the up movement of the packing plunger. The flow of liquid continues through the control valve when the latter is in neutral position (Figure 3). At the required period, the triple valve N, O, P, returns to normal position (Figure 3) by the action of spring P' when the excess liquid pressure through L' is restored to normal upon the completion of the up movement of plunger or ram B, so that there is no flow through the relief valve at the period of operation of the power plunger and of the operation of the packing plunger except when such relief valve acts for a brief period to permit the reduction of pressure for the automatic reversal of the control valve I to take place by the inertia of the weight K'.

The operation of holding the packing plunger into contact with the material in one of the material cylinders C or C' during the period of time required for the ram to travel upwardly for the major part of its upstroke may be performed by the operator moving the lever K from the position of Figure 4 to the neutral position of Figure 3, in which case the liquid from the pump flows idly from pipe H, through port s, passage v, chamber m, and return pipe H', the several parts coacting to retain plunger G' in the lowered position and upon the material so as to preclude expansion of said material within the cylinder.

Although I have shown and described fluid actuated means for controlling the valve I,

such means being dependent upon the return movement of the ram, it is to be understood that my invention comprehends broadly a mechanism, either mechanical or fluid actuated, whereby the upstroke of the ram sets into action the return movement of the packing plunger. 70

Having thus fully described the invention, what I claim as new and desire to secure by Letters Patent is:

1. In a hydraulic press, the combination with a hydraulic extruding ram including a controlling valve for effecting the extruding stroke and the return stroke, and a shiftable material cylinder, of a hydraulic packing plunger operable within said material cylinder for applying pressure for a determined time upon a mass to be compressed whereby the density of said mass is increased prior to the action upon the condensed mass of said hydraulic extruding plunger, and fluid pressure means responsive to a return stroke of the extruding ram for effecting the withdrawal from the material cylinder of said packing plunger. 80

2. In a hydraulic press, the combination with a hydraulic extruding ram and a hydraulic packing plunger, of a controlling valve mechanism for said hydraulic packing plunger, operable manually for setting the packing plunger into action, and controllable by fluid pressure of the extruding ram mechanism for effecting the return movement of said packing plunger. 95

3. In a hydraulic press, the combination with a hydraulic extruding ram and a hydraulic packing plunger, of a controlling valve mechanism for said hydraulic packing plunger and operable for applying pressure to material during the travel of said extruding plunger and for retaining said material under pressure on the return of said extruding ram, and means responsive to the return of the extruding ram for effecting the return movement of the packing plunger. 100

4. In a hydraulic press, the combination with a hydraulic extruding ram and a hydraulic packing plunger, of a control valve mechanism for said packing plunger, operable to impart the working and return movements to said packing plunger, said valve mechanism being under fluid pressure and retained in determined positions by such pressure, and means responsive to the return movement of the extruding plunger for reducing the fluid pressure on the control valve mechanism, whereby said valve mechanism is operable automatically to effect the return of the packing plunger to normal position. 110

5. In a hydraulic press, the combination with a hydraulic extruding ram, and a hydraulic packing plunger, of a hydraulic valve for controlling the movement of said packing plunger by hydraulic pressure, said hydraulic valve including a by-pass in liquid 125

- connection with said hydraulic extruding ram and said valve being responsive to a variation in fluid pressure for effecting the return movement of said packing plunger.
5. In a hydraulic press, the combination with a hydraulic extruding ram, and a hydraulic packing plunger, of a controlling valve for said packing plunger, means for manually operating said control valve, means responsive to the action of said extruding plunger for relieving said control valve from the action of fluid pressure, and means for reversing said valve upon a reduction of pressure thereon.
10. 6. In a hydraulic press, the combination with a hydraulic extruding ram, and a hydraulic packing plunger, of a controlling valve for said packing plunger, means actuated by said extruding plunger mechanism for relieving said control valve from the restraint of pressure, means for reversing said control valve, and plunger operated means for restoring the control valve to neutral position.
15. 7. In a hydraulic press, the combination with a hydraulic extruding ram, and a hydraulic packing plunger, of a controlling valve for said packing plunger, means actuated by said extruding plunger mechanism for relieving said control valve from the restraint of pressure, means for reversing said control valve, and plunger operated means for restoring the control valve to neutral position.
20. 8. In a hydraulic press, the combination with a hydraulic extruding ram, and a hydraulic packing plunger, of a control valve for said packing plunger, said control valve being seated by fluid pressure, means for relieving said control valve from fluid pressure, said means being responsive to the return movement of said extruding ram, means associated with said control valve, whereby it is reversed when relieved from the effect of pressure, and plunger operated means for restoring the control valve to neutral position.
25. 9. In a hydraulic press, the combination with a hydraulic extruding ram, and a hydraulic packing plunger, of a control valve for said packing plunger, said control valve being under the influence of hydraulic pressure, a by-pass connected with the extruding plunger and said control valve, relief valve in said by-pass and means operable for reversing said control valve upon a reduction in pressure thereon.
30. 10. In a hydraulic press, the combination with a hydraulic extruding ram, of a hydraulic packing plunger, and fluid actuated means responsive to the movement of said extruding ram for effecting the automatic return of said packing plunger to normal position.
35. 11. In a hydraulic press, the combination with charging means and a hydraulic extruding ram, of a hydraulic packing plunger co-operable with said charging means, and fluid-actuated means responsive to the movement of the extruding ram for effecting the withdrawal of the packing plunger from said charging means.
40. 12. In a hydraulic press, the combination with material-carrying means, and a hydraulic extruding ram, of a hydraulic pack-
- ing plunger operable for retaining material under pressure during the effective stroke of the extruding ram, and fluid-actuated means for effecting the automatic withdrawal of the packing plunger upon the return stroke of the extruding plunger.
45. 13. In a hydraulic press, the combination with material-carrying means, and a hydraulic extruding ram, of a hydraulic packing plunger operable for retaining material under pressure during the effective stroke of the extruding ram, and means responsive to a variation in the fluid pressure effected by said extruding plunger for effecting the withdrawal of the packing plunger concurrently with the return of said extruding plunger.
50. 14. In a hydraulic press, the combination with an extruding ram including valve mechanism for controlling fluid pressure to effect the extruding stroke and the return stroke of said ram, and a shiftable material cylinder, of a fluid pressure actuated packing plunger operable for a determined time by such fluid pressure in applying a compressive force to a mass present within said material cylinder, whereby the density of said mass is increased by the action of fluid pressure prior to the extrusion of said mass by the extruding ram, and a separate controlling valve for initiating the action of fluid pressure on said packing plunger.
55. 15. In a hydraulic press, the combination with a hydraulic extruding ram including valve means for controlling fluid pressure in effecting the extruding movement and the return movement of said ram, and a shiftable material cylinder, of a hydraulic packing plunger including controlling means whereby the compression stroke is influenced by fluid pressure, and means actuated by a variation in fluid pressure for effecting the return stroke of the packing plunger concurrently with the return stroke of the extruding plunger.
60. 16. In a hydraulic press, the combination with a hydraulic extruding ram including valve means for the fluid pressure, and a shiftable material cylinder, of a hydraulic packing plunger co-operable with said cylinder when the latter is shifted to a charging position, a separate valve for controlling said packing plunger, means for relieving said separate valve from fluid pressure, and means for shifting said separate valve upon a variation of the fluid pressure.
65. 17. In a hydraulic press, the combination with an extruding ram including valved means for controlling the action of fluid pressure on said ram, and a shiftable material cylinder, of a hydraulic packing plunger, a separate valve for controlling the action of fluid pressure on said packing plunger to initiate the compressing stroke thereof, means for reducing pressure on said separate valve, means for shifting said separate valve upon the variation of said fluid pressure, and

plunger operated means for returning the separate valve to normal position.

18. In a hydraulic press, the combination with an extruding plunger mechanism including a valve for controlling the action thereon of fluid pressure, and a shiftable material cylinder, of a hydraulic packing plunger, a separate valve for controlling the action of fluid pressure on said packing plunger to initiate the compressing stroke thereof, a by-pass with a relief valve, said by-pass being co-operable with the fluid pressure means of said packing plunger, whereby the fluid pressure is varied on the separate valve, and means for actuating the separate valve.

19. In a hydraulic press, the combination with an extruding ram including a valve for controlling the action of fluid pressure thereon, and a material cylinder, of a hydraulic packing plunger mechanism including a separate valve for initiating the action of the fluid pressure in imparting the compressing stroke to the packing plunger, means for effecting variation in the pressure on said separate valve, and a weighted arm for reversing the separate valve upon such variation in pressure.

20. In a hydraulic press, the combination with a hydraulic extruding ram, and a shiftable material cylinder, of a hydraulic packing plunger mechanism including a separate valve for controlling the action of fluid pressure to initiate the compressing stroke of said plunger within said cylinder, means for effecting a variation of the fluid pressure on said separate valve, whereby said separate valve is controlled to reverse the travel of the packing plunger, and valve actuating means coacting with said packing plunger for restoring said separate valve to neutral position.

21. In a hydraulic press, the combination with a hydraulic extruding ram, and shiftable material cylinder, of a hydraulic packing plunger mechanism including a separate valve for controlling the action of fluid pressure in effecting the movement of said packing plunger, means for effecting the variation in the pressure of said fluid on the separate valve, means for reversing said valve, and a member operated by the packing plunger for restoring said separate valve to neutral position.

In testimony whereof I have hereto signed
55 my name this 7th day of July, 1926.

JOSEPH DE FRANCISCI.
